UNITED STATES PATENT OFFICE.

MINNIAFFEE J. JARDEE AND ROBERT J. COWELL, OF ST. JOSEPH, MISSOURI.

OIL BURNER.

Application filed August 21, 1922. Serial No. 533,138.

To all whom it may concern:

Be it known that we, MINNIAFFEE J. JARDEE and ROBERT J. COWELL, citizens of the United States, residing at St. Joseph, in the county of Buchanan and State of Missouri, have invented certain new and useful Improvements in Oil Burners, of which the following is a specification.

Our invention relates to improvements in oil burners and one object is to provide a device of this character having but few parts which are not likely to get out of order and can be manufactured and marketed at small cost.

15 A further object is to provide a burner in which kerosene, distillate and other hydrocarbon oils may be economically consumed and wherein efficient combustion is had, so that said burner will not become 20 clogged with carbon, or other waste elements present in the fuel.

Other objects will hereinafter appear, and in order that the invention may be fully understood, reference will now be had to 25 the accompanying drawing, in which:

Fig. 1 is a longitudinal sectional view of the device.

Fig. 2 is a plan view.

In carrying out the invention, we employ 30 a generating chamber 2 which may be of relatively oblong shape as shown to fit in the fire box of a stove, or it may be circular to fit within the fire box of a furnace. The upper portion of said generating chamber 35 2 has a marginal flange 4 which forms a shallow basin 6 in the upper portion of the chamber 2.

8 designates a relatively short pipe connected to the upper portion of the generating chamber 2 through the intermediary of a bushing 10, the upper end of said pipe 8 being equipped with a T-fitting 12 to which 40 a feed pipe 14 is connected through the intermediary of a return fitting 16.

45 18 designates a burner in the form of a pipe connected at one end to the T-fitting 12 and closed at its opposite end by suitable means such as a cap 20. The burner 18 is provided at its under portion with a 50 discharge orifice 22 turned downwardly towards the chamber 2 and the feed pipe 14.

In practice oil is admitted to the generating chamber 2 through the feed pipe 14, the return fitting 16, the T-fitting 12, and the 55 pipe 8, and a small quantity is permitted

to flow from the orifice 22 into the basin 6. The oil in the basin 6 is then ignited to heat the chamber 2 and vaporize the oil therein. The vapor ascends through the pipe 8 and enters the burner 18 from which it discharges through the orifice 22 and freely intermingles with the immediate surrounding atmosphere, thereby forming a combustible mixture which becomes ignited, the resultant flame impinging against the feed pipe 14 and the top of the generating chamber 2 and thereby heating the same and continuing the process of vaporizing the fuel oil as it enters said chamber 2. As the fuel oil is heavier than the vapor it descends into the generating chamber 2 through the pipe 8, while at the same time the vapor being lighter than the oil, ascends through said pipe 8 and enters the burner 18 from which it is discharged through the orifice 22, as above stated. The heat produced by the flame is so intense that the supply of oil flowing through the feed pipe 14 may be reduced to a minimum without danger of the flame becoming extinguished, and hence 70 a saving in fuel may be effected in mild weather when considerable heat is not required. Economy is also had from the fact that the oil in the generating chamber 2 is reduced to a highly heated vapor before 75 escaping from the orifice 22 in the burner 18, thereby eliminating the waste which accompanies the burning of more or less of the fuel oil in liquid form.

From the foregoing description it will be 80 understood that we have produced a burner embodying the advantages above pointed out, and while we have shown and described the preferred form of our burner, we reserve the right to make such changes as 85 properly fall within the spirit and scope of the appended claims.

Having thus described our invention, what we claim and desire to secure by Letters Patent, is:

1. A device of the character described consisting of a generating chamber having a basin at its upper portion, a dual oil and vapor pipe connected to said chamber, a feed pipe connected to the first-mentioned pipe, and a burner also connected to the first-mentioned pipe and having an orifice directed toward the chamber.

2. A device of the character described consisting of a generating chamber, a pipe 105

extending upwardly from said chamber, a feed pipe extending over the chamber and connected to the upper portion of the first-mentioned pipe, and another pipe connected to the upper portion of the upwardly extending pipe and extending over the feed pipe and the generator and having an orifice directed towards the top of the chamber.

In testimony whereof we affix our signatures, in the presence of two witnesses.

MINNIAFFEE J. JARDEE.
ROBERT J. COWELL.
